UNITED STATES PATENT OFFICE.

ALFONS MUSIOL, OF TABOR, AUSTRIA-HUNGARY.

INCUBATOR.

No. 868,686.

Specification of Letters Patent.

Patented Oct. 22, 1907.

Application filed May 10, 1907. Serial No. 372,985.

To all whom it may concern:

Be it known that I, ALFONS MUSIOL, a subject of the Emperor of Austria, residing in Tabor, Kingdom of Bohemia, Austrian Empire, have invented a new and useful Incubator, of which the following is a specification.

My invention relates to improvements in hatching ovens, with the objects of a cheap and well working hatching device with a complete and reliable regulation of temperature and regulation of air, by heating it directly with a small petroleum lamp, or the like. I attain these objects by the device illustrated as an example in the accompanying drawing, in which—

Figure 1 is a vertical section of the oven, and Fig. 2 another vertical section of the same oven, being at right angles to the former one.

Inside a double box having the space between its walls 1 and 2 filled with cheap insulation (chaff or the like), is interposed an oven, which consists of a suitably shaped body 4, 5 of zinc or the like, with an air-space between its side-walls 4 and the bottom 5 and between said box. This air-space between the outward double box and the oven, as shown in cross section in Fig. 1, is heated directly by a small petroleum lamp 10 or the like, the cylinder of which reaches through an opening 25 into said air cushion, said opening 25 as well as other openings 21 being arranged for the circulation of air and for the removal of the products of ignition. The apparatus may be provided with supports 26 at convenience.

The interior of the oven 4, 5 is accessible by its door 24, and is ventilated by openings 8 and 9 and a chimney 11, 12, which can be more or less closed by a light disk 15 of aluminium for instance. Disk 15 is held normally closed by a steel band, 16. Opening the chimney 12 is preferably attained by an electromagnet 14 of which said band 16 forms the armature, its circuit having its source in a battery 19 or the like. In the same circuit is also a contact-thermometer 13 inside the oven, and a controlling button 17 outside on the top. The valve 15 may also be withdrawn, for opening the chimney, in turning the small lever or

pawl 18 with the fingers, while by the electric device the opening of the chimney proceeds automatically. If the heat near the eggs reaches a given limit of degrees, the contact-thermometer 13 closes the circuit, the electromagnet 14 attracts the band 16 and by this opens the chimney 12, and the inside of the oven becomes cooled by the draft of atmospheric air, which enters freely through the openings 8, 9.

20 is an ordinary thermometer.

Pressing the controlling contact-button 17 with the finger will show at any moment whether the circuit is in order.

The eggs repose in the oven preferably upon perforated plates 7, which may be withdrawn or put in the oven through the door 24. Vessels with water 22, may be provided upon the bottom 5 of the oven, to produce the necessary moisture inside the oven.

I am aware that, prior to my invention, hatching ovens have been made. I therefore do not claim such a combination broadly; but

I claim:

1. An incubator comprising a casing having double walls having heat insulating material therebetween, a metallic box supported in said casing so as to leave a space between two of its sides and its bottom and said casing, means for heating the air in said space, said casing having openings in its top and bottom, means for regulating the temperature automatically and mechanically and means for supplying moisture to the box.

2. An incubator comprising a casing, a metallic hatching box supported in said casing so as to leave a space between two of its sides and its bottom and the casing, means for heating said space, said box having an opening leading to the atmosphere, a chimney connected with the box, a valve normally closing said chimney, an electric circuit, an electro-magnet therein, a steel band carrying the valve and acting as the armature for the electro-magnet and a thermostat in said box and forming part of the electric circuit.

In testimony whereof I affix my signature in presence of two witnesses.

ALFONS MUSIOL
